UNITED STATES PATENT OFFICE.

ROBERT E. HAMMOCK, OF ALLEN, OKLAHOMA, ASSIGNOR OF ONE-SIXTH TO WILLIAM M. PEGG, ONE-SIXTH TO MORDECIA B. DONAGHEY, AND ONE-SIXTH TO MICAGAH P. DONAGHEY, ALL OF ALLEN, OKLAHOMA.

RAIL-FASTENER.

1,046,586

Specification of Letters Patent.

Patented Dec. 10, 1912.

Application filed June 8, 1912. Serial No. 702,606.

To all whom it may concern:

Be it known that I, ROBERT E. HAMMOCK, a citizen of the United States, residing at Allen, in the county of Pontotoc and State of Oklahoma, have invented certain new and useful Improvements in Rail-Fasteners, of which the following is a specification, reference being had to the accompanying drawings.

10 This invention relates to rail fasteners and has for its object to provide a combined rail supporting chair and joint wherein the use of fish plates and connecting bolts through the web of the rail as is usually employed in 15 devices of this character, is eliminated.

Another object of the invention resides in the provision of an improved rail fastener which will admit of the expansion and contraction of the rails due to changes in temperature, but which will at the same time maintain the opposed ends of the rails in alignment.

A still further object of the invention is to provide a rail fastener which is simple in 25 construction, may be easily and quickly applied to the rails and can be produced at comparatively small cost.

With the above and other objects in view as will become apparent as the description 30 proceeds, the invention consists in certain constructions, combinations and arrangements of the parts that I shall hereinafter fully describe and claim.

For a full understanding of the invention 35 reference is to be had to the following description and accompanying drawing, in which—

Figure 1 is a perspective view of my improved rail fastener showing the same applied to the rails and secured upon the supporting tie; Fig. 2 is a section taken on the line 2—2 of Fig. 1; Fig. 3 is a longitudinal section through the side of the chair; Fig. 4 is a section taken on the line 4—4 of Fig. 3; 45 and Fig. 5 is a detail fragmentary perspective view of one of the rails.

Corresponding and like parts are referred to in the following description and designated in the accompanying drawing by like 50 reference characters.

Referring in detail to the drawing 5 designates the adjacent rails to be connected and secured upon the supporting tie 6 by

means of my improved fastener. The fastening device comprises a chair plate 7 having a central depending enlargement 8. This enlarged portion of the chair plate 7 is adapted to be seated in a recess 9 provided in the upper surface of the tie. Upon the longitudinal edges of the chair plate 7 the inwardly extending flanges 10 are formed for engagement upon the base of the rails 5. Longitudinal metal bars 11 are adapted to be arranged upon these flanges of the chair plate after the rails have been seated thereon. These bars are substantially coextensive in length with the chair plate 7. One of the bars 11 is provided upon its inner edge and centrally between its ends with a transversely disposed pin or lug 12 which is preferably formed integrally with the bar. The other of the bars 11 upon the opposite side of the rails 5 is provided upon its inner edge with a socket or recess 13 to receive the end of said lug. It will be noted from reference 75 to Fig. 3 that the lug 12 is of octagonal form in cross section whereby the upper and lower inclined or beveled faces 12' are produced. The opposed ends of the rails 5 are provided in their web portions with recesses 14 which correspond in form to the cross 80 sectional outline of one side of the lug 12, said recesses being provided with beveled or inclined walls 14'. These inclined walls of the recesses in the rail webs are adapted to 85 coat with the beveled faces 12' of the lug 12 whereby, when the rails are in their normal positions upon the chair plate, the tread surfaces thereof are disposed in the same longitudinal plane thereby presenting a 90 smooth and unbroken bearing surface for the train wheels over the joint.

The base flanges of the rails 5 are provided in their edges with longitudinal recesses 15 with which spike receiving openings 16 and 17 in the flanges 10 of the chair plate and in the bars 11 respectively are adapted to coincide. The base or body portion of the chair plate 7 is also provided with openings through which the spikes 100 indicated at 18 are adapted to be driven into the tie, thereby firmly and securely holding the chair plate in position upon the same.

By providing the elongated spike receiving recesses in the edges of the base flanges

of the rails, relative longitudinal movement of the rails upon the chair plate is permitted upon the expansion and contraction of the metal caused by temperature changes. The transverse bolt 12 which is disposed in the recesses 14 in the abutting ends of the rails serves as additional supporting means for the rail ends and prevents pounding of the same upon the chair plate when the wheels pass over the joint. At the same time, this lug will admit of the limited longitudinal or creeping movement of the rails, but effectually prevent any relative vertical movement thereof.

In assembling the device upon the rails, the chair plate 7 is first moved inwardly upon the end of one rail and the other rail is laid in position in alinement with the first rail. The chair plate 7 is then moved upon the latter rail until the same is disposed in the position shown in Fig. 1 of the drawing. The chair plate is now arranged upon the tie with the projection 8 thereof seated in the recess of the tie and the bars 11 placed in position. After the lug 12 on one bar has been inserted through the recesses in the webs of the rails, and disposed in the socket of the other bar, said bars and the chair plate are securely spiked upon the tie in the manner above described.

From the foregoing it is thought that the construction and manner of application of my improved rail fastener will be clearly understood. The device is simple in construction, may be easily and quickly applied and will at all times maintain the rails in proper alinement, and thus obviate serious accidents caused by the spreading of the rails.

While I have shown and described the preferred construction and arrangement of the various elements employed, it will be understood that the invention is susceptible of considerable modification without de-

parting from the essential features or sacrificing any of the advantages thereof.

Having thus described the invention, what is claimed is:

1. The combination with the rails, of a chair plate upon which the same are adapted to be seated, said chair plate having inwardly extending flanges engaging over the base of the rails, a supporting tie provided with a recess in its upper surface, said chair plate having an enlarged portion to be seated in said recess, the base flanges of the rails having longitudinal recesses in their edges, and longitudinal bars arranged upon the flanges of the chair plate on opposite sides of the rails, said bars and the chair plate having spike receiving openings coinciding with the recesses in the rail flanges, whereby the same may be secured upon the tie.

2. The combination with the rails having recesses in their abutting web portions, said recesses being provided with opposed inclined walls, of a chair plate upon which the rails are adapted to be seated, said chair plate having inwardly extending flanges to engage over the base of the rails, longitudinally extending bars arranged upon the flanges of the chair plate on opposite sides of the rails, a transversely disposed lug centrally formed upon the edge of one of the bars and adapted to be received in the recesses of said rails, said lug being of polygonal form in cross section and provided with beveled faces to coact with the inclined walls of said recesses, and means for securing said bars and the chair plate upon the rail supporting tie.

In testimony whereof I hereunto affix my signature in the presence of two witnesses.

ROBERT E. HAMMOCK.
